Fig. 1.

Fig. 2.

To all whom it may concern:

Be it known that I, Sam H. Bordelon, a citizen of the United States, residing at Chicago, in the county of Cook and State of Illinois, have invented a new, original, and ornamental Design for a Spoon or the Like, of which the following is a specification, reference being had to the accompanying drawing, forming part thereof.

In the drawing:

I claim:

The ornamental design for a spoon or the like, as shown.
